UNITED STATES PATENT OFFICE

114,950

DESIGN FOR AN INSTRUMENT CABINET

Joseph F. Haynie, Jr., El Dorado, Ark.

Application August 3, 1938, Serial No. 79,082

Term of patent 14 years

To all whom it may concern:

Be it known that I, Joseph F. Haynie, Jr., a citizen of the United States of America, residing at El Dorado, county of Union, and State of Arkansas, have invented a new, original, and ornamental Design for an Instrument Cabinet, of which the following is a specification, reference being had to the accompanying drawing, forming part thereof, wherein:

Figure 1 is a perspective view of an instrument cabinet, showing my new design.

Figure 2 is a transverse sectional view, taken on the line 2—2 of Figure 1.

I claim:

The ornamental design for an instrument cabinet, as shown.

JOSEPH F. HAYNIE, JR.
